UNITED STATES PATENT OFFICE

JOSEPH DOBOI, OF PARIS, FRANCE

NOTEBOOK

Application filed May 31, 1927, Serial No. 195,404, and in France February 2, 1927.

This invention relates to a note book in which the notes are to be written on a paper band which is interchangeably mounted on two rollers so that the portion of the paper band, on which the writing is to be done, can be replaced, according to requirement by a fresh portion.

This note-book is characterized by the manner in which the paper band is mounted and by the fact that the central portion of said notebook may be used as cigarette-case, purse, powder-box and the like.

An embodiment of the invention is illustrated, by way of example, in the accompanying drawing in which—

Fig. 1 is a transverse section showing the different elements of the device separately.

Fig. 2 shows in a similar section the assembled note-book.

Fig. 3 is a section on line A—A of Fig. 2.

Fig. 4 is a section on line B—B of Fig. 2.

The note-book comprises a flat case 3 of metal, tortoise-shell, or celluloid, to be opened at the side and comprising an aperture 5 over which the interchangeable paper-band *d* extends which is mounted on rollers *b*, *c*. These two rollers are arranged at the two ends of an element 2 which fits accurately into the case 3 but is adapted to be easily separated from the same. This element 2 comprises, with this object in view, two compartments 2^a, 2^a designed to receive the rollers *b*, *c* respectively, the journals *b'*, *c'* of these rollers engaging with grooves 4, 4 in the partitions 35 which form the ends of the two compartments 2^a, 2^a. Between these two compartments extends a solid, perfectly plane part 2^b which forms the support over which the paper-band unwinds and which, when the element 2 is mounted in case 3, is situated accurately behind the aperture 5 of this case 3. The central portion of this element 2 remains free to be used as a cigarette-case purse, powder-box or the like.

To bring the paper-band, which has been mounted on the two rollers *b*, *c* into the correct position, it is sufficient, the element 2 having been removed from case 3, to place the journals *b'*, *c'* of said rollers into the grooves 4, 4 so that the paper-band between these two

rollers is lying on the support 2^b. After this, the element 2, is inserted into the case 3 which is then closed by shutting the lid. The portion of the paper-band which rests on the support 2^b stands behind the aperture 5 of the case so that it can be used for writing notes. When this portion of the paper-band is full, another portion can be substituted for the same by rotating the fluted wheels *g* the circumference of which projects into suitable slots.

A flexible blade 6 exerts an elastic pressure upon each roller to press the same against the wall of the case corresponding to the unwound portion of the paper band.

I claim:—

A note-book, comprising in combination an outer casing composed of two equal box-like parts hingedly connected the one with the other one of said parts having a large aperture, a platen removably mounted in said casing under said aperture, a support at the right side and a support at the left side of said platen, said supports being made in one piece with said platen, said supports being box-like open at the upper side and having each a vertical slot in each end wall downwardly extending from the top edge, said slots being adapted to support a pair of rollers having a paper strip attached thereto, a pocket readily accessible when said casing is opened formed under said platen by said supports at the right and left sides of said platen.

In testimony whereof I affix my signature.

JOSEPH DOBOI.
